United States Patent Office

Des. 180,084
Patented Apr. 16, 1957

180,084

CANDELABRA OR SIMILAR ARTICLE

Gilbert Josephson, White Plains, N. Y.

Application June 22, 1956, Serial No. 42,003

Term of patent 14 years

(Cl. D48—2)

FIG. 1

FIG. 2

Fig. 1 is a plan view of a candelabra showing my new design; and

Fig. 2 is a front elevational view thereof, the side and rear elevational views corresponding in all respects to the front elevational view.

I claim:

The ornamental design for a candelabra or similar article, substantially as shown.
